DESIGN FOR A MACARONI OR SIMILAR ARTICLE

Gennaro Cirillo, Brooklyn, N. Y.

Application April 20, 1935, Serial No. 56,479

Term of patent 7 years

To all whom it may concern:

Be it known that I, Gennaro Cirillo, a citizen of the United States and a resident of Brooklyn, in the county of Kings and State of New York, have invented and produced a new, original, and ornamental Design for Macaroni or Similar Article, of which the following is a specification, reference being had to the accompanying drawing, forming part thereof, wherein:—

Fig. 1 is a side elevational enlarged view of a macaroni or similar article showing my new design;

Fig. 2 is a view of one end thereof; and
Fig. 3 is a view of the other end thereof.

I claim:

The ornamental design for a macaroni or similar article as shown.

GENNARO CIRILLO.
